UNITED STATES PATENT OFFICE

JOHN PUDLINER, OF ALLENtown, PENNSYLVANIA, ASSIGNOR TO BREY & KRAUSE MANUFACTURING COMPANY, OF ALLENtown, PENNSYLVANIA, A CORPORATION OF PENNSYLVANIA

DESIGN FOR A TUMBLER HOLDER

Application filed November 24, 1931. Serial No. 41,838. Term of patent 7 years.

To all whom it may concern:

Be it known that I, JOHN PUDLINER, a citizen of the United State, residing at Allentown, in the county of Lehigh and State of Pennsylvania, have invented a new, original, and ornamental Design for a Tumbler Holder, of which the following is a specification, reference being had to the accompanying drawings, forming a part thereof.

I claim:

The ornamental design of a tumbler holder substantially as shown.

JOHN PUDLINER.
